CLAIM

The ornamental design for a food container, as shown and described.

DESCRIPTION

FIG. 1 is an isometric view of a food container.

FIG. 2 is a front elevation view of the food container of FIG. 1.

FIG. 3 is a rear elevation view of the food container of FIG. 1.

FIG. 4 is a left side view of the food container of FIG. 1.

FIG. 5 is a right side elevation view of the food container of FIG. 1.

FIG. 6 is a top plan view of the food container of FIG. 1; and, FIG. 7 is a bottom view of the food container of FIG. 1.

The claim is limited to the shaded surfaces only. Portions of FIGS. 1 through 7 are shown in broken lines illustrating portions of the article that form no part of the claimed design. The broken lines immediately adjacent the shaded surfaces represent boundaries of the claim and form no part thereof.
